UNITED STATES PATENT OFFICE.

AARON SCHLANG, OF BROOKLYN, NEW YORK.

GARMENT-HANGER.

No. 884,617.

Specification of Letters Patent.

Patented April 14, 1908.

Application filed December 21, 1907. Serial No. 407,472.

To all whom it may concern:

Be it known that I, AARON SCHLANG, a citizen of the United States, and residing at Brooklyn, in the county of Kings and State 5 of New York, have invented certain new and useful Improvements in Garment-Hangers, of which the following is a specification, such as will enable those skilled in the art to which it appertains to make and use the same.

10 The object of this invention is to provide a garment hanger of the usual form adapted to be suspended by a hook from any suitable support, and which is designed to contain moth balls or other germicide or insect destroying material.

15 The invention is fully disclosed in the following specification, of which the accompanying drawing forms a part, in which the separate parts of my improvement are designated by suitable reference characters in each of the views, and in which:—

20 Figure 1 is a side view of my improved garment hanger partly in section, Fig. 2 a plan view thereof, and;—Fig. 3 a section on the line 3—3 of Fig. 1.

25 In the practice of my invention I provide a garment hanger *a*, comprising a top member *b* and bottom member *c*. The top member *b* may be used independently of the bottom member if desired, and said top member is of what is known as the usual bow-shape and comprises a bottom part *b*² and top part *b*³.

30 The bottom part *b*² of the hanger member *b* is provided in the top thereof with a longitudinal channel or chamber *b*⁴ adapted to contain moth balls *b*⁵ or any other germicide or insect destroying or preventing material, and the bottom side walls of the channel or 35 chamber *b*⁴ are perforated or provided with apertures *b*⁶.

40 The top part *b*³ of the hanger member *b* is adapted to close the channel or chamber *b*⁴, and is secured to the bottom part by a bolt *c*² which is passed therethrough and provided at its upper end with a suspending hook *c*³, and at its lower end with a nut *c*⁴, and the top part *b*³ of the hanger member *b* is also slightly shorter than said hanger member, 45 and is provided at its opposite ends with tongues *b*⁷ which fit in corresponding recesses in the end portions *b*⁸ of the part *b*², and the ends of the part *b*² of the top member of the hanger are provided with downwardly directed extensions *b*⁹ in which the bottom member *c* is secured. One end of the bot-

tom member *c* is provided with a trunnion *c*⁵ adapted to enter a corresponding recess in the one end portion *b*⁹ of the top member of the hanger, and the opposite end portion *b*⁹ of the top member of the hanger is provided with a laterally ranging groove or recess *c*⁶ adapted to receive a corresponding trunnion *c*⁷ on the end of the member *c*, and pivoted at *c*⁸ is a catch *c*⁹ adapted to engage the trunnion *c*⁷ and hold it in the groove or recess *c*⁶.

45 The bottom member *c* of the hanger consists of a rod or bar, and as thus constructed the said bottom member may be detached when not desired for use, and the top member *b* may be used separately as a complete hanger, or the said parts may be used together as shown in Fig. 1 whenever desired.

50 In practice a coat, vest or other garment may be suspended from the top member *b* of the hanger in the usual manner, and when desired trousers or other garments may be suspended from the bottom member of the hanger.

55 The entire hanger is preferably composed of wood and may be made of any desired dimensions, and in this way I provide a hanger of the usual form which also serves as a receptacle for moth balls or similar material, and by which the said moth balls or other material is held in the best possible position in order to accomplish the result for which the same is intended.

60 Having fully described my invention, what I claim as new and desire to secure by Letters Patent, is:—

65 1. A garment hanger of the usual form comprising top and bottom parts, the bottom part being provided with a longitudinal channel or chamber in the top thereof which is closed by the top part, the walls of said channel or chamber being perforated.

70 2. A garment hanger of the usual form comprising top and bottom parts, the bottom part being provided with a longitudinal channel or chamber in the top thereof which is closed by the top part, the walls of said channel or chamber being perforated, and said parts being held together by a bolt passed centrally through the same and provided at its upper end with a hook.

75 3. A garment hanger of the usual form comprising top and bottom parts, the bottom part being provided with a longitudinal channel or chamber in the top thereof which is closed by the top part, the walls of said channel or chamber being perforated, and

2
said parts being held together by a bolt
passed centrally through the same and pro-
vided at its upper end with a hook and at its
lower end with a nut, the ends of the top part
being also provided with tongues which fit in
corresponding recesses in the ends of the bot-
tom part.

In testimony that I claim the foregoing as

my invention I have signed my name in pres-
ence of the subscribing witnesses this 20th 10
day of December 1907.

AARON SCHLANG.
